UNITED STATES PATENT OFFICE.

JOSEPH AUSTIN, OF LONG BRANCH, NEW JERSEY.

OIL-GUARD FOR SEWING-MACHINE TREADLES.

SPECIFICATION forming part of Letters Patent No. 395,198, dated December 25, 1888.

Application filed April 5, 1888. Serial No. 269,702. (No model.)

To all whom it may concern:

Be it known that I, JOSEPH AUSTIN, a citizen of the United States, residing at Long Branch, in the county of Monmouth and State 5 of New Jersey, have invented new and useful Improvements in Oil-Guards for Sewing-Machine Treadles, of which the following is a specification.

This invention has for its object to provide 10 simple, inexpensive, and novel means for catching and collecting the oil dripping from the pivots of the treadle of a sewing-machine to avoid soiling the floor and carpet or other floor-covering.

15 The object of my invention I accomplish in the manner and by the combination of devices hereinafter described and claimed, reference being made to the accompanying drawings, in which—

20 Figure 1 is a vertical section showing part of the treadle-shaft and its connections with my invention combined therewith. Fig. 2 is a detail perspective of the drip-trough detached.

25 In the said drawings the reference-numeral 1 denotes the treadle of any known form of sewing-machine, that shown being of the Singer type, although my invention is by no means limited in its application to this or any 30 other specified construction. The numeral 2 designates the treadle-bearings, and 3 denotes the pitman, which is connected in any usual manner to a toe or bracket, 4, on the treadle.

35 Arranged beneath the treadle is a drip-trough, 5, composed of a narrow metallic receptacle having its ends 6 inclined upward and outwardly, flanges 7 being formed continuously upon the body portion 5, as well as 40 upon the inclined ends 6.

To detachably suspend the trough from the machine-frame 10, I provide the following

simple and economical means: Each of the bent ends 6 is provided near its upper end with a transverse wire, 8, secured in the flanges 45 of such bent end, and the suspension-wires 9 are each bent to form a curved portion and two arms having hooked extremities detachably hooked into engagement with the transverse wires 8. The suspension-wires are 50 adapted to straddle bearings which connect the lateral braces with the machine-frame 10.

I purpose arranging a drip-cup, 12, beneath the point where the lower end of the pitman 3 connects with the toe or bracket 4 on the 55 treadle to catch the oil-drippings at this point.

The devices shown constitute an extremely simple, cheap, effective, readily-detachable, and convenient drip-vessel capable of attachment to machines of any pattern.

Prior to my invention drip-troughs have been suspended beneath treadles, and such, therefore, I do not broadly claim, my invention residing in the novel construction of the 65 trough and the described devices for suspending the same from the machine-frame.

What I claim is—

The combination, in a drip-guard for pivots of a treadle, of a drip-trough comprising the 70 horizontal portion having bent ends, said portion and ends having opposite side flanges, a transverse wire secured to the side flanges of each bent end, and the suspension-wires each provided with a curved portion extending 75 into two arms having hooked extremities engaging the said transverse wires, substantially as shown and described.

In testimony whereof I affix my signature in presence of two witnesses.

JOSEPH AUSTIN.
